RECEPTACLE

Joseph V. Wuestman, Union, N. J.

Application February 18, 1947, Serial No. 729,329

3 Claims. (Cl. 120—108)

1

This invention relates to improvements in receptacles; and the invention has reference, more particularly, to a novel construction of receptacle adapted to serve as a container for fountain pen and pencil sets and for other purposes.

Matching fountain pens and pencils are frequently commercially distributed together as pen and pencil sets, in which case a pen and pencil forming a set are packed together in a container. In many cases the container is suitable, when opened, to display the set on a retail store counter, and, when closed, to serve as a package in which the set is delivered to a purchaser. After serving these purposes, the containers, as heretofore provided, have no further utility so far as the pen and pencil sets are concerned, and, as is generally the case, the containers are thrown away by the purchasers after the pen and pencil sets are removed therefrom.

Having these circumstances in view, it is an object of this invention to provide a novel construction of receptacle which is not only adapted to provide a container for a fountain pen and pencil set which is suitable for use as a commercial display means and delivery package therefor, but which, after these purposes have been served, may be converted by the purchaser of the set into an attractive and serviceable pen and pencil stand or holder suitable for desk use.

Illustrative embodiments of this invention are shown in the accompanying drawings, in which:

Fig. 1 is a plan view of one form of the novel receptacle according to this invention, the same being shown in the closed condition in which it is adapted to serve as the package in which a contained pen and pencil set is delivered to a purchaser; Fig. 2 is a longitudinal sectional view, with parts in elevation, showing the receptacle in said closed condition; Fig. 3 is a plan view of said receptacle as opened and arranged for commercial display of a contained pen and pencil set, and in which open condition the same is also converted for use as a pen and pencil stand or holder suitable for desk use; Fig. 4 is a longitudinal sectional view, with parts in elevation, of the thus opened and converted receptacle; and Fig. 5 is a transverse sectional view showing the use of the opened and converted receptacle as a pen and pencil stand or holder suitable for desk use.

Fig. 6 is a transverse sectional view, with parts in elevation, showing a modified form of receptacle according to this invention, with parts shown by full lines as disposed in open condition suitable for commercial display of a contained pen and pencil set, and the same parts being

2

shown by broken lines in closed condition to form a delivery package for the pen and pencil set; and Fig. 7 is a transverse sectional view of the same as arranged for use as a pen and pencil stand or holder suitable for desk use.

Similar characters of reference are employed in the hereinabove described views, to indicate corresponding parts.

Referring first to Figs. 1 to 5 inclusive of the drawings, one embodiment of this invention which is illustrated thereby comprises a main body formed by a bottom portion 10 and upstanding wall portions 11 of suitable and preferably ornamental conformation which rise from the marginal parts of the bottom portion 10, and which define an interior chamber 12. At their inner sides, said wall portions 11 are provided, along the lower parts thereof, with inwardly projecting or offset portions 13, the tops of which

10 provide seating shoulders 14, spaced downwardly from the upper interior margins of said wall portions. Said main body thus formed may be made of any suitable material, such e. g. as metal, wood, glass, plastic composition or the like, and the

15 wall portions 11 may be either solid or hollow formation.

The reference character 15 indicates a plaque of suitable thickness. Said plaque is dimensioned and shaped to be removably fitted into the upper 20 interior of the chamber 12 of the main body, so as to rest upon the seating shoulder 14, and thus serve as a cover adapted to close said chamber. Formed in one face of said plaque 15 are suitably located and shaped countersunk cavities or 25 troughs 16 and 17. In one said cavity or trough, e. g. 16, may be initially laid and suitably temporarily secured a fountain pen F, and in the other cavity or trough, e. g. 17, may be initially laid and suitably temporarily secured a pencil P. Said 30 plaque 15 is also provided, to preferably extend from the same face thereof in which said cavities or troughs 16 and 17 are formed, with suitably located and shaped, outwardly open, socketed stand or holder members 18 and 19, which project exteriorly from said plaque face. Said stand or holder members are preferably arranged to project angularly oblique to the plane of said plaque face. Said stand or holder members may be optionally formed as either separate or integral 35 parts of the plaque, but preferably comprise separate tubular elements, the lower ends of which are inserted and affixed in receiving sockets 20 with which the plaque is provided. The tubular elements preferably are of such length that they 40 extend into closely abutting contact with the bottom

tom portion 10 of the main body when plaque 15 is seated in closing relation to said main body, as shown in Fig. 2, with the holder members 18 and 19 inwardly presented. In order to effect this close abutment when the preferred inclined disposition of the holder members is adopted, the mouth of each tubular element should be beveled as shown particularly in Figs. 3 and 5. The purpose of close abutment is to seal the holder members against entrance of foreign substances, such as dirt, dust, lint, or small articles which may be stored in the interior chamber 12 in the course of normal desk use and whose presence in the sockets would interfere with insertion of the pen and pencil. Said plaque may also be made of any suitable material, but is preferably made of a molded plastic material which possesses an appearance adapted to contrast with that of the main body.

When using the receptacle for service as a commercial or counter display of the contained pen and pencil set, the plaque 15 is deposited within the main body with that face thereof which contains the cavities or troughs 16 and 17 outwardly presented, so that the pen F and pencil P held in the latter may be observed (see Fig. 3).

When using the receptacle for service as a package in which the contained pen and pencil set is delivered to a purchaser thereof, the plaque 15 is removed from the main body, and, after being inverted, is reassembled with the latter so that the plain face thereof is outwardly presented and the face thereof which contains the cavities or troughs 16 and 17, and the pen and pencil held therein, is opposed to and within the chamber 12 of said main body, and so that the stand and holder members 18 and 19 are also concealed within the chamber. As thus arranged the plaque serves as a cover or closure for the main body chamber (see Figs. 1 and 2).

After the purchaser of the thus delivered pen and pencil set removes the pen and pencil from the receptacle for use, said receptacle may be retained for service as a desk stand or holder for a pen and pencil. To condition the receptacle for the latter use, the plaque 15 is again reversed and replaced in the main body, with the stand or holder members 18 and 19 exteriorly projecting therefrom (see Fig. 4); whereupon a pen and pencil or like articles may be inserted in the stand or holder members 18 and 19 to project therefrom so as to be quickly and conveniently accessible for use (see Fig. 5). It will be obvious that, when the receptacle is used as a desk stand or holder for a pen and pencil or like articles, since the plaque is easily removable from the main body, the chamber 12 may also be then used as a storage compartment for miscellaneous small articles or supplies desired to be kept conveniently at hand on the user's desk.

In Figs. 6 and 7 is shown a somewhat modified form of the novel receptacle suitable to serve the several functions above mentioned. In this modified form, the main body is substantially the same in structure as that already above described, and comprises a bottom portion 10' having upstanding wall portions 11', and internal offset portions to provide the seating shoulders 14'. Said wall portions 11' define the interior chamber 12'. Cooperative with said main body is a plaque 15', said plaque being hingedly connected by a hinging pintle 21 to and between opposed parts of the wall portions 11'. As thus hingedly connected with the main body, the plaque 15' may be up-swung to standing position (see full line representation thereof in Fig. 6), or to a down-swung

position (see broken line representation thereof in Fig. 6), in which latter position it seats upon the seating shoulders 14', so as to close the underlying main body chamber 12'. Formed in the inner or underface of said plaque 15' are suitably located and shaped countersunk cavities or troughs 16' and 17' in which may be initially laid and suitably temporarily secured a fountain pen and pencil. Formed in the free outer part or end of the hinged plaque 15' are suitably located, outwardly open holder sockets 22, which extend into the body of the plaque from the edge of said outer part or end thereof and which also are sealed against entrance of foreign substances in the chamber closing position of the plaque by abutment of the mouths of said sockets against the contiguous wall portion 11' of the body.

When using the last described modified form of the receptacle for service as a commercial or counter display of the contained pen and pencil set, the plaque 15' is up-swung to upstanding position, so that its inner or underface is outwardly presented, whereby to expose to view, the pen and pencil set mounted thereon. When using the modified receptacle for service as a package in which the contained pen and pencil set is delivered to a purchaser thereof, the plaque 15' is down-swung to closed position, thus enclosing the contained pen and pencil set within the chamber 12' of the main body.

After the purchaser of the delivered pen and pencil set removes the pen and pencil from the receptacle, said receptacle may be conditioned for use as a desk stand or holder for a pen and pencil, merely by up-swinging the plaque 15' to an upwardly and forwardly inclined position (see Fig. 7). The plaque 15' may be retained in such position by providing sufficient frictional resistance to relative movement between the same and the main body in connection with the hinge connection between these parts. When the plaque 15' is disposed in the afore said upwardly and forwardly inclined position, the outwardly open ends of the holder sockets 22 are accessibly exposed for insertion and reception of a pen and pencil, which, when entered therein will be supported by the plaque so as to be quickly and easily accessible for use (see Fig. 7).

From the above it will be understood that the instant invention provides a very useful and novel receptacle structure which is well adapted to optionally serve as a commercial display and delivery package, and which thereafter may be converted for service as a pen and pencil holder of desk use.

As various changes may be made in the embodiments above described and shown in the accompanying drawings without departing from the scope of this invention as defined by the following claims, it is to be understood that all matter hereinbefore set forth or shown in the accompanying drawings is to be interpreted as illustrative and not in a limiting sense.

I claim:

1. A receptacle for the purposes described comprising a main body formed by a bottom portion and wall portions upstanding therefrom to define an upwardly open interior chamber, said wall portions having inwardly offset means to provide a seating shoulder within the interior chamber, a reversible plaque removably seated on said seating shoulder in closing relation to said interior chamber, said plaque being provided with outwardly open socket means disposed to project from a face thereof, said socket means, when said plaque is assembled with said main body with said face

outwardly presented, being exposed for endwise insertion therein of a pen, pencil or like article, whereby to support the latter in longitudinal projection from said socket means.

2. A receptacle for the purposes described comprising a main body formed by a bottom portion and wall portions upstanding therefrom to define an upwardly open interior chamber adapted to contain articles such as pens, pencils or the like for storage and shipment, said wall portions having inwardly offset means to provide a seating shoulder within the interior chamber in spaced relation to the upper edges and bases of said wall portions, a reversible plaque adapted to be removably seated in either of its reversed positions on said seating shoulder in closed relation to said interior chamber, said plaque being provided with outwardly open socket means of tubular form projecting from a face thereof to an extent not exceeding the depth of the interior chamber below said seating shoulder whereby said socket means is adapted to be sheltered in said chamber when the plaque is seated in one position, said socket means, when said plaque is seated in its reversed position, being exposed for endwise insertion

10

15

therein of a pen, pencil or like article, whereby to support the latter in longitudinal projection from said socket means.

3. A receptacle for the purposes described as defined in claim 2, wherein the tubular socket means is obliquely inclined to the plane of the plaque and has its open mouth beveled so as to abut snugly against the bottom portion of the main body when sheltered with the body chamber.
